UNITED STATES PATENT OFFICE.

PIERRE TRÉMOULIÉRE, OF BORDEAUX, FRANCE.

TAG AND TAG-FASTENER.

SPECIFICATION forming part of Letters Patent No. 416,813, dated December 10, 1889.

Application filed January 11, 1888, Serial No. 260,409. (No model.) Patented in France August 6, 1887, No. 185,167.

To all whom it may concern:

Be it known that I, PIERRE TRÉMOULIÉRE, a citizen of the French Republic, residing at Bordeaux, in said French Republic, have invented a new and useful Improvement in Fasteners for Labels, Tags, &c., (for which I have obtained Letters Patent in France under date of August 6, 1887, No. 185,167,) of which the following is a specification.

10 My invention relates to that class of fasteners adapted for use in fastening labels, tags, and other like indices to merchandise or to packages of merchandise.

15 It is the object of the invention to provide a simple yet efficient device by means of which a label or a tag, or a similar device bearing certain information, may be readily and securely fastened to merchandise or packages of merchandise.

20 The invention consists in a fastener composed of a head constructed to hold or retain the label or tag, or to which such label or tag may be secured in any desired manner, and of a prong or pin, or a plurality of such, by 25 means of which the fastener is pinned to the merchandise or to packages of such, substantially as hereinafter described and claimed.

25 Referring to the accompanying drawings, which form a part of this specification, Figures 1 and 1^a are isometric views of one form 30 of fastener constructed according to my invention. Figs. 2 and 3 are respectively top and bottom plan views showing the fastener applied to a label or card. Fig. 4 is an isometric view of a fastener constructed like 35 that shown in Figs. 1, 2, and 3, but provided with two prongs or pins. Figs. 5 and 6 are views similar to those shown in Figs. 2 and 3, with a fastener such as is shown in Fig. 5.

40 The fastener A consists, essentially, of a headed pin, whose head a is so constructed that a card, label, or tag may be firmly secured thereto, and said fastener may have a plurality of pins or prongs a'.

As shown in Figs. 1, 1^a, 2, 3, 5, and 6, the 45 head a of the fastener consists of a metallic plate bent into U shape to form a clamp, between which the edge of a card or label is secured or clamped.

The head a of the fastener may be provided 50 with any desired number of pins a', and two or more such fasteners may be employed to secure a card or label to merchandise and hold it thereon perfectly flat, in which case two or more of the edges of the card will be metal- 55 bound and protected by the binding, so as not to be readily torn off.

The fastener can be made very cheaply, as it may be stamped out of suitable sheet metal.

It is obvious that a fastener constructed as 60 described may be readily applied with its card or label to all merchandise into which the pins are insertible or to packages of such merchandise. It may also be secured to other goods by using the pins as a means for attaching the fastener, as by bending the pin or pins around the merchandise. It is, however, especially designed for use on wearing-ap- 65 parel, to avoid the labor of sewing on the labels. 70

Having described my invention, what I claim is—

As an improved article of manufacture, a tag provided with a fastener having a U-shaped head for the reception of one edge of the 75 tag, and one or more prongs or pins extending in a straight line from the same for securing the tag to the merchandise, substantially as described.

In testimony that I claim the foregoing I 80 have hereunto set my hand this 22d day of December, 1887.

PIERRE TRÉMOULIÉRE.
